UNITED STATES PATENT OFFICE.

ARLINGTON MOORE, OF NEW YORK, N. Y., ASSIGNOR, BY MESNE ASSIGNMENTS, TO
MAXMOOR CORPORATION, A CORPORATION OF DELAWARE.

PROGRESSIVE-IMPULSE INTERNAL-COMBUSTION ENGINE.

Application filed July 3, 1925. Serial No. 41,442.

My invention is of an internal combustion engine in which progressive impulses are obtained by means of the provision of gas pockets in the cylinder walls.

5 In accordance with my invention, the compressed charge of an internal combustion engine is distributed between the usual compression space over the piston head and a series of pockets provided in the cylinder wall within the height of piston head travel, the pockets so provided serving to obtain increased volume of fuel charge in the cylinder.

15 The charge compressed over the piston is first ignited, and as the piston travels down on the power stroke, the portions of the charge, which were retained in the pockets on the compression stroke, are ignited from the burning charge over the piston head as 20 said pockets are uncovered by the downwardly traveling piston. In this way a series of power impulses are produced, and the sustained impulses, extending over a considerable proportion of the power stroke of 25 the piston, produce an effect which resembles the action of the Diesel type of engine wherein the fuel is introduced into the cylinder during at least a considerable portion of the downward movement of the piston on 30 the power stroke.

The invention enables the same or greater continuity of power to be obtained with considerable reduction in cylinder diameter and in engine size and weight generally, re- 35 presses detonation, and, by providing for sustained impulse production of power pro- 40 ducing pressure during the downward travel of the piston on the power stroke reduces the strains and jars to which the engine is subjected, thus repressing engine torque 45 reaction, makes possible the use of lighter parts with smoother operation and longer life of the engine, and secures a more uniform and better distributed delivery of 50 power, particularly at low engine speeds and under heavy loads. Thus in the case of an automobile engine, for example, the capacity for climbing hills on high gear with wide open throttle is materially improved by my 55 invention. Increased volumetric efficiency is also obtained as compared with engines having cylinders of the usual construction.

In the accompanying drawing Fig. 1 is a vertical sectional view showing an embodiment

ment of my invention, and Fig. 2 is a trans- 55 verse section on the line 2—2, Fig. 1.

Reference character 10 designates a cylinder of a preferably multi-cylinder internal combustion engine, 12 the piston, 14 the connection rod, and 16 one of the valves. The engine selected for illustration is of the L-head type, but the invention is applicable as well to valve-in-head and other types of engine.

The principle constructional feature of 65 the improved engine resides in the provision of the series of pockets in the cylinder wall. As shown, eight of the pockets are provided, one set of four pockets 18 toward the upper part of the cylinder wall, distributed 70 substantially equi-distant therearound and a second set of four pockets 20 somewhat further down and arranged in staggered relation to the pockets 18 of the upper set. Various other arrangements, as spiral, etc., 75 arrangements may be resorted to, if desired.

These pockets are preferably made abruptly recessed at the top, as indicated at 22, and preferably on a more gradual taper toward the bottom, as indicated at 24.

80 The upper pocket or pockets 18 are so arranged that they will have been sealed by the piston in its upward passage prior to the earliest possible point of ignition. Ignition is preferably from a spark plug 26 85 which is preferably located over the center of the piston head. As shown in Fig. 1 the upper pockets 18 are closed when the piston is about 45° of the rotation of crank shaft 28 from the upper limit of piston 90 movement. The lowermost pocket or pockets, as pockets 20, are located sufficiently high up on the cylinder wall to enable the power impulse from combustion of gases trapped therein to become effective mate- 95 rially before the piston reaches the bottom of the power stroke.

The piston is well provided with rings to prevent loss of gas from the pockets. In the form shown, the piston 12 has two rings 100 32 at the top and two more rings 34 near the bottom. The rings may be pinned substantially as shown to prevent any possibility of catching on the pocket walls. As the cylinder surface is materially reduced 105 there is a corresponding material reduction in loss of power by friction.

On the exhaust stroke the pockets 18, and

- 20 trap exhaust gas, which on the intake stroke is admixed, together with exhaust gas remaining in the compression space 36 over the piston head, with the incoming charge.
- 5 If desired, the exhaust valve may be open at the beginning of the intake stroke to allow additional exhaust gas to pass backwardly into the cylinder for the purpose of minimizing detonation, or additional exhaust gas
- 10 may be admitted in other ways for this purpose.

On the compression stroke, portions of the charge, more or less compressed, according to height of piston stroke reached before

15 the respective pocket is sealed by the piston, are trapped in the pockets 18, 20.

On the power stroke the charge in compression space 36 over the head is ignited, the resulting pressure acting to force the

20 piston down, and as the pockets 18 are uncovered the portions of the charges contained therein are also ignited and burned, producing a supplemental power impulse, and this is repeated as pockets 20 are un-

25 sealed. The pockets being relatively abruptly recessed at the top produces a downward reaction as ignition takes place, and being of taper recess at the bottom prevents any substantial reaction in the opposite di-

30 rection.

The preferable way of producing the pockets is by casting the cylinders with the pockets therein, and if desired, the metal walls may be of substantially uniform thick-

35 ness, the walls back of the pockets being extended into the water jacket space somewhat, substantially as shown; or, if desired, the pockets can be cut or machined in the cylinder wall, in which case they can be given a high finish to good advantage. They should preferably be smoothly finished when made in the operation of casting the cylinder.

If the compression space 36 over the

45 piston head is not reduced when providing

the gas pockets, compression pressure there-
in will be reduced by part of the charge
being retained in the gas pockets, but at
least as great power is obtained as when
all the charge is compressed in the space

50 36. By cutting down the compression space,
however, as by machining away part of the
inner face of the cylinder head, better ad-
vantage can be taken of the increase in
volume of charge and more economy and

55 efficiency obtained through the provision of
the gas pockets in the cylinder wall. Thus
the power delivery of a high compression
engine may be obtained without any sub-
stantial increase in compression pressures,

60 and the detonation which would accompany
the high compression pressures is avoided.

I claim:

1. Cylinder for internal combustion en-
gine having gas pockets in its wall abruptly

65 recessed at the top and relatively taperingly
recessed at the bottom.

2. Cylinder for internal combustion en-
gine having in its wall below the upper

70 limit of piston head travel and above the lower limit of piston head travel a plurality of sets of gas pockets, abruptly recessed at their upper ends and relatively taperingly recessed at their lower ends.

3. Cylinder for internal combustion en-
gines, having a plurality of sets of recesses

75 in its inner wall, the recesses in adjacent sets being arranged in substantially stag-
gered relation.

4. Cylinder for internal combustion en-
gines, having a plurality of sets of gas pock-
ets in its inner wall abruptly recessed at the

80 top and relatively taperingly recessed at the bottom, the pockets in adjacent sets be-
ing arranged in substantially staggered

85 relation.

In testimony whereof, I have signed my
name hereto.

ARLINGTON MOORE.
